ARTICLE HOLDING APPARATUS

George W. Soderman, West Englewood, N. J., assignor to Western Electric Company, Incorporated, New York, N. Y., a corporation of New York

Application October 20, 1948, Serial No. 55,577

3 Claims. (Cl. 113—99)

1

This invention relates to article holding apparatus, and more particularly to apparatus for holding fragile plates such as synthetic crystals during the process of soldering lead wires thereto.

The scarcity of quartz crystals for use in communication equipment activated research work in the field of synthetic piezo-electric crystals. As the result of this work, synthetic crystals commercially known as EDT crystals grown in a solution of ethylene diamine tartrate were adopted as a suitable substitute for quartz in the manufacture of crystal units. The selection of synthetic crystals for use in place of quartz, necessitated new developments in machines and methods of processing the synthetic crystal, as those previously employed for processing quartz crystals could not be utilized for this purpose. The method of attaching lead wires to synthetic crystal plates is the principal divergence in their manufacture from that of quartz crystal plates. To protect these fragile synthetic crystal plates from thermal-shock while the lead wires are being attached, they must be gradually heated to a temperature at which they can withstand the heat required for the soldering operation and then slowly cooled to room temperature.

An object of the invention is to provide a holding apparatus for fragile articles, such as synthetic crystals, wherein the article is protected from mechanical abuse and which acts as a thermal-reservoir during heating and cooling cycles to protect the plate from thermal-shock.

With this and other objects in view, the invention comprises an apparatus for holding fragile articles including a main member having an aperture therein, a companion member having an aperture therein cooperating with the main member to firmly support an article therebetween and resilient elements normally urging the members toward each other under like pressure to apply uniform pressures to the article to hold it firmly in place.

More specifically, the apparatus includes a main member with like recesses at its ends and having parallel grooves in one surface thereof spaced equal distances from the recesses. The main member has spaced locating pins receivable in apertures of the companion member to locate the companion member accurately relative to the main member and to align its aperture with the aperture of the main member. The companion member is also provided with recesses in its ends, the recesses in both members receiving the split cylindrical springs which are substantially equal

in length to the notches serving to hold the members in proper superimposed positions, their edges extending into the parallel grooves of the main member and like parallel grooves in the companion member. The companion member is smaller in size than the main member whereby the main member may be received in grooves of fixed position holding elements to hold the main member against movement while four actuating pins of actuating means are moved simultaneously through apertures in the main member, positioned adjacent the corners of the companion member, to move the companion member uniformly away from the main member against the forces of the springs to facilitate in the loading and unloading of the fragile articles between the members. The apparatus for loading the synthetic crystal plate in the holding apparatus is disclosed in the applicant's copending application, Serial No. 55,578, filed October 20, 1948. The unloading apparatus is shown in detail in the copending application of A. Fermanian and A. P. Jurnak, Serial No. 55,562, filed October 20, 1948.

Other objects and advantages will be apparent from the following detailed description when considered in conjunction with the accompanying drawings, wherein:

Fig. 1 is an isometric view of the article holding apparatus, portions thereof being removed;

Fig. 2 is a top plan view of the apparatus;

Fig. 3 is a longitudinal sectional view taken along the line 3—3 of Fig. 2;

Fig. 4 is an end elevational view of the apparatus illustrating one form of mechanism for separating the members for loading and unloading articles therebetween; and

Fig. 5 is an isometric view of an article after lead wires have been mounted thereon by the aid of the holding apparatus.

Referring now to the drawing, attention is first directed to the illustration in Fig. 5 of an article 10, which in the present embodiment of the invention is a synthetic crystal and to which lead wires 11 have been secured by the aid of the apparatus. The apparatus includes a main member 12, rectangular in general contour and having recesses 14 formed in the ends thereof in off center aligned positions as illustrated in Fig. 2. The main member has a central elongate aperture 15 open through one side of the member by a slot 16. Grooves 17 are formed in the outer surface of the member and extend the full width of the member at positions equally spaced from the recesses 14. Apertures 20 are

formed in the member 12 adjacent the corners thereof to receive actuating pins illustrated in Fig. 4 and identified by reference numerals 21. Locating pins 23 are fixedly mounted on the member 12 and are receivable in apertures 24 of a companion member 25 to accurately locate the companion member with respect to the main member 12.

The companion member 25 although similar in contour to the main member 12 is smaller in length and width whereby the ends of the main member may be received in grooves 28 of fixedly mounted holders 29 to hold the main member during actuation of the pins 21 to force the members apart. The companion member 25 has recesses 30 similar to the recesses 14 formed in its ends to receive holding elements 31 which are split cylindrical springs with apertures 32 disposed diametrically opposite the split portions of each spring to reduce the force, initially embodied in the spring, to that desired for holding the members 12 and 25 against the article 10 when placed therebetween. Parallel grooves 34 are formed in the outer surface of the companion member 25 to receive their respective edges of the springs 31 while the other edges of the springs enter the grooves 17 and in this manner, the springs are held against displacement longitudinally of the apparatus, the recesses 14 and 30 holding the springs against displacement laterally of the apparatus. In a like manner, the springs 31 being substantially equal in length to the recesses, cooperate with the pins 23 in holding the members properly positioned. The companion member 25 is provided with a central aperture 35 similar in contour to the aperture 15 of the main member 12 and in alignment therewith, the aperture 35 also being opened to the same side of the apparatus through a slot 36. Concaved recesses 37 and 38 are formed in the members 25 and 12 as illustrated in Fig. 3 to facilitate in positioning the lead wires 11 in engagement with the plate 10 and the application of heat to the wires adjacent the points where they are to be soldered to the plate during the soldering process.

The holding apparatus including the main member 12 and the companion member 25 presents smooth parallel inner surfaces of these members to receive the fragile articles 10 singly therebetween with portions of the articles to receive the lead wires 11 disposed in registration with the apertures 15 and 35. Through the forces embodied in the springs 31, uniform force will be applied through the members 12 and 25 to the article 10 firmly holding the article between the members whereby it is protected from mechanical abuse by the necessary handling of the article during the process of mounting the lead wires 11 upon the opposing surfaces thereof. Furthermore, the members 12 and 25 are formed of suitable metal to act as a thermal-reservoir for the article during heating and cooling cycles necessary for the soldering process to protect the plate or article 10 against thermal-shock.

The article 10 is positioned between the members 12 and 25 when they are in their open positions caused by the actuation of the pins 21 flexing the springs 31. When the article is accurately located, the pins 21 are moved gradually in a given direction to allow the force of the springs 31 to move the companion member against the article applying uniform pressures to the article. After the lead wires 11 have been secured in place, the apparatus may again be opened by

the aid of the fixed position holders 29 holding the main member 12 against movement while the pins 21 enter the apertures 20 to abut the companion member 25 at the corners thereof uniformly moving the companion member against the forces of the springs 31 until it is free of the article. The completed article may then be removed from the apparatus, moving the lead wires 11 through the slots 16 and 36.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for removably holding fragile articles while parts are secured thereto comprising a first article engaging member having an aperture therein open to one side of the member through a slot, a second article engaging member having an aperture therein open to one side of the member through a slot, the apertures in the members exposing portions of opposing faces of the article whereby parts may be secured thereto, and the slots providing exits for the parts, springs normally urging the members toward each other, and means to cause relative positioning of the members to maintain alignment of the apertures and their slots, the first member having pin receiving apertures at spaced positions therein through which pins may be moved to move the second member away from the first member against the force of the springs to open the holder for the successive loading and unloading of articles between the members.

2. An apparatus for holding synthetic crystal plates for the soldering of lead wires thereto the apparatus comprising companion metallic members with opposing flat surfaces to engage opposing faces of a synthetic crystal plate, and aligned apertures open to adjacent sides of the members through slots whereby portions of the synthetic crystal plate to which lead wires are to be soldered are exposed and the synthetic crystal plate with the lead wires may be removed from between the members with the lead wires moving through the slots, and split cylindrical springs engaging portions of the members upon opposing sides of the apertures and slots to firmly hold the synthetic crystal plate therebetween to protect it against mechanical abuse and whereby the metallic members may be heated with the synthetic crystal plate to various temperatures to protect the crystal plate against thermal-shock.

3. An apparatus for removably holding fragile articles while parts are secured thereto comprising a first member having a flat article engaging surface and an aperture therein open to one side of the member through a slot, a second member having a flat article engaging surface, cooperating with the article engaging surface of the first member to engage opposing faces of the article, and an aperture therein open to one side of the member through a slot, the apertures in the members exposing aligned portions of opposing faces of the article whereby parts may be secured thereto and the slots providing exits for the parts, split cylindrical springs extending about opposing ends of the members to the members in uniform pressure contact with the article, and projections carried by one of the members and receivable in apertures of the other member to maintain

alignment of the first mentioned apertures and slots, the first member having pin receiving apertures therein through which pins may be moved to engage and move the second member away from the first member against the forces of the springs to open the holder for the successive loading and unloading of articles between the members.
